F. E. WELLMAN,
LIQUID HEATING FURNACE,
APPLICATION FILED APR. 9, 1918.

1,335,774.

Patented Apr. 6, 1920.

Frank E. Wellman

Attorney

UNITED STATES PATENT OFFICE.

FRANK E. WELLMAN, OF KANSAS CITY, KANSAS, ASSIGNOR TO THE KANSAS CITY GASOLINE COMPANY, OF KANSAS CITY, KANSAS, A CORPORATION OF KANSAS.

LIQUID-HEATING FURNACE.

1,335,774.

Specification of Letters Patent.

Patented Apr. 6, 1920.

Application filed April 9, 1918. Serial No. 227,555.

To all whom it may concern:

Be it known that I, FRANK E. WELLMAN, a citizen of the United States, residing at Kansas City, in the county of Wyandotte and State of Kansas, have invented certain new and useful Improvements in Liquid-Heating Furnaces, of which the following is a specification, reference being had therein to the accompanying drawing.

10 My invention relates to oil heating furnaces and especially to heaters for oil refining stills or retorts.

An object of the invention is to provide a heating arrangement in which the hot gases are caused to remain in contact with the surfaces to be heated a sufficient length of time to effect a maximum amount of absorption of heat from the gases.

Another object is to increase the length 20 of travel of the hot gases in contact with the surfaces to be heated without undue resistance to the flow of the hot gases and with a minimum amount of baffling walls and surfaces and a consequent reduction of 25 the amount of heat absorbed in baffling.

A further object is to provide a combination and arrangement of a plurality of retort tubes and heating means therefor, operable to effect an even distribution of heat 30 to the several tubes.

Other objects of the invention will be apparent from a perusal of the following specification and the accompanying drawings forming a part thereof.

35 My invention is illustrated in the accompanying drawings in which:

Figure 1 is a front elevation with the front wall partly broken away to show the interior.

40 Fig. 2 is a cross sectional view taken on the line 2—2 of Fig. 1.

In the drawings, 1 indicates the main heating chamber near the bottom of which are provided a series of separate combustion chambers 2 which extend across the main chamber from the front to the rear thereof and communicate therewith near their rear ends through Lentz bars 3, each combustion chamber being provided with 45 suitable fuel burning means such as the burners 20. The tubular retort elements 4 are arranged within the main chamber 1 in two horizontal layers 5 and 6 one above the other, the tubes 4 extending across the chamber from side to side and projecting

through the side walls 7 and 8 to the outside of the furnace where they are provided with flanged couplings 9 for connection with other apparatus. The lower layer 6 is spaced from the front wall 10 as shown at 60 11 and extends back close to the rear wall 12 while the upper layer 5 is correspondingly spaced from the rear wall as indicated at 13 and extends to the front of the chamber close to the front wall. At the 65 front of the furnace is provided a series of stacks 14 communicating with the main chamber 1 at the upper forward end thereof, one above each of the combustion chambers 2. The tubes in each layer are arranged 70 close to each other as shown so that while some of the hot gases from the combustion chambers is allowed to circulate between them, the layer as a whole will act as a baffle. Thus with the layers arranged one 75 above the other and spaced from opposite sides of the chamber and the combustion chambers and stacks arranged as shown, the hot gases from the combustion chambers are induced to take the path indicated by 80 the arrows in Fig. 2, with a reduced cross flow of gases between the tubes of a layer sufficient to effect an even heating of the entire surface of the tubes. By regulating the relative amount of heat generated in 85 the several combustion chambers, any tendency to variations in temperature along the length of the tubes may be offset and an even longitudinal distribution of heat effected. It is to be noted here that instead 90 of two layers, one layer of tubes may be used, which single layer would be positioned as the layer 6 while the flues or stacks 14 would be located at the rear of the heating chamber to properly direct the draft around 95 the single layer.

While I have herein shown and described a particular embodiment of my invention for the purpose of disclosure, it is to be understood that I do not limit myself to such 100 particular embodiment but contemplate all such modifications and variations thereof as fairly fall within the scope of the appended claims.

Having thus described my invention what 105 I claim and desire to secure by Letters Patent is:

1. A liquid heater comprising a main heating chamber, a plurality of horizontal layers of parallel tubes one above the other, 110

each layer being spaced from one side of the chamber and extending across the chamber transversely of the tubes close to the opposite side, adjacent layers being spaced from opposite sides and all the layers extending completely across the main chamber longitudinally of the tubes, a plurality of combustion chambers and individual heating means therefor arranged below said 10 main chamber and communicating therewith through openings below the lowermost layer of tubes opposite the spaced edge of said lowermost layer, a plurality of flues or stacks communicating with the heating chamber at points above the uppermost layer opposite the spaced end of said upper layer, and regulating means for said heating means for regulating the relative amount of heat generated in the several 15 combustion chambers, whereby any tendency 20

to variation in temperature along the length of the tubes may be offset and an even longitudinal distribution of heat effected.

2. A liquid heater comprising a main combustion chamber, a plurality of liquid heating tubes arranged parallel to each other and extending uninterruptedly across said chamber and through the walls thereof, a plurality of combustion chambers situated below said tubes and extending transversely thereof, and means for directing the exit of heated gases from the said heating chamber, said combustion chambers communicating with the heating chamber at one side thereof, said tubes being arranged close together to form a baffle to direct the flow of heated gases to the other side. 25 30 35

In testimony whereof I affix my signature.

FRANK E. WELLMAN.
